UNITED STATES PATENT OFFICE.

ORIN KELLY, OF WELLSTON, OHIO

INTERNAL-COMBUSTION ENGINE.

No. 895,184.

Specification of Letters Patent.

Patented Aug. 4, 1908.

Application filed April 19, 1907. Serial No. 369,139.

To all whom it may concern:

Be it known that I, ORIN KELLY, a citizen of the United States, residing at Wellston, in the county of Jackson and State of Ohio, 5 have invented a new and useful Internal-Combustion Engine, of which the following is a specification.

This invention relates to internal combustion engines, and has for its principal object 10 to provide an engine in which the advantages of both the two cycle and four cycle types of engines are combined.

It is a well known fact to those familiar 15 with internal combustion engines, that the two cycle type of engine is, mechanically considered, far superior to the four cycle type, because of its greater simplicity and fewer working parts, and chiefly because the explosion or impulse is given every revolution 20 as against an impulse every two revolutions in the four cycle type of engine, but on account of the fact that it has not been hitherto possible to sufficiently clear the cylinder of the dead gases of a previous explosion before the charge for the next impulse, the two cycle engine has a tendency to choke up and otherwise not work efficiently except at low speeds.

In constructing an engine in accordance 30 with the present invention, provision is made for the employment of an additional scavenging piston, by which the waste products of combustion are forced from the cylinder without interfering with the introduction of 35 the fresh charge.

With this and other objects in view, as will more fully hereinafter appear, the invention consists in certain novel features of construction and arrangement of parts, herein- 40 after fully described, illustrated in the accompanying drawing, and particularly pointed out in the appended claims, it being understood that various changes in the form, proportions, size and minor details of the 45 structure may be made without departing from the spirit or sacrificing any of the advantages of the invention.

In the accompanying drawings:—Figure 1 is a sectional elevation of an engine provided 50 with a scavenging piston constructed in accordance with the invention, the main piston being shown near the completion of the working stroke. Fig. 2 is a similar view of the cylinder and pistons showing the position as 55 assumed by the pistons near the completion of the compression stroke. Fig. 3 is a detail per-

spective view looking toward the under side of the scavenging piston. Fig. 4 is a view similar to Fig. 2, illustrating a slight modification.

Similar numerals of reference are employed to indicate corresponding parts throughout the several figures of the drawings.

The crank case 10 is provided with bearings for a shaft 11 carrying a crank 12 that 65 is connected by a rod 13 to a piston 14 of the ordinary construction, and said piston is arranged to travel within a cylinder 15 provided with a water jacket or other cooling means of the usual type.

Leading into the crank case is a valved inlet 16, and from the top of the cylinder leads a valved exhaust 17. The charge admitted to the crank case is partly compressed on the working stroke of the piston and passes 75 through the transfer ports 18 to the upper side of the piston at the completion of the working stroke.

Arranged within the cylinder is a scavenger piston 20, said piston being provided 80 with suitable packing rings 21 and having at the bottom an annular rib 22 and a central lug 23, which ride against the top of the piston proper during the working stroke. The rib 22 is provided with numerous passages 24 85 in order to permit the entrance of the fresh charge between the two pistons.

At the explosion chamber end of the cylinder are arranged a number of cushions 27 which may be formed of asbestos or other 90 slightly yieldable material in order to prevent noise when the scavenger piston strikes against the head. The wall of the cylinder is provided with a number of small by-pass ports 29, of greater height than the width of 95 the piston 20, so that the fresh charge may pass from the lower to the upper side of said piston 20 in readiness for the next working stroke.

It will be noted that the exhaust port 17 100 is so arranged with reference to the by-pass ports and piston that the piston will close the exhaust port before opening the by-pass ports, so that any escape of the fresh charge through the escape port will be prevented.

In the position shown in Fig. 1, the two pistons 14 and 20, have nearly completed the working stroke, and the space between the two pistons is about to be placed in communication with the transfer ports 18, these being 110 preferably arranged at equal distances from each other in order to prevent any tilting or

jamming of the scavenger piston through excess pressure at any point. The exhaust port is open, and the products of combustion will flow from the cylinder through said exhaust port, thereby reducing the pressure at the explosion chamber end of the cylinder, and when this occurs the gases confined between the two pistons will immediately start to move the piston 20 upward and the latter will travel toward the explosion chamber end of the cylinder, sweeping all of the burned gases from the cylinder. This movement is assisted by the pressure of the fresh charge which enters above the piston 14 as soon as the latter is moved slightly further down from the position shown in Fig. 1, so that the complete upward travel of the scavenger piston will be insured. As the scavenging piston nears the limit of its upward movement, it will close the exhaust port 14 and this will open the by-pass 29 of which there may be any desired number, and by this time the main piston is approaching the limit of compression movement, and the gas compressed in advance of said piston will be forced through the by-pass ports to the space between the top of the scavenging piston, and the head of the explosion chamber, whereupon another explosion takes place, and the operation is repeated as before.

While it is preferred to operate the scavenging piston by pressure of gases and thus avoid outside connections, the scavenging piston may be provided with a rod 34 extending through the head of the explosion chamber, as shown in Fig. 4, said rod being operated in any suitable manner to accomplish the desired result. One mechanism is illustrated in Fig. 4 and consists of a spring arranged between the head of the explosion chamber and a flange or collar 35 at the head of the rod. When the scavenging piston moves down under the force of the working stroke, the spring is placed under stress, and when the exhaust valve is open, the spring will expand and will move the scavenging

piston upward and force the exploded charge out of the cylinder. It will be seen that all of the functions of supply, compression, expansion and exhaust are as thoroughly and completely accomplished and the dead gases are as thoroughly swept from the cylinder and the wasting of live gases as effectually prevented as in any engine of four cycle design, while the simplicity of design and frequency of impulse of the two cycle engine are retained.

The construction shown in Fig. 4 is such that the charge may be taken in as in the ordinary four cycle type of engine, thus avoiding the necessity of initial compression of the charge in the crank case. It is obvious that the returning device for the scavenging piston, which in the present instance is shown in the form of a spring, may be sufficiently powerful to effect a complete return of the scavenging piston without the aid of the pressure from the charge and may move in the same manner as the ordinary piston of a four cycle engine moves during the suction stroke. While the spring has been illustrated as one means of securing this result, it is obvious that any other suitable mechanical connections may be employed for the same purpose.

I claim:-

In an internal combustion engine, a cylinder, a piston, a scavenging piston, an inlet port for directing the explosive charge between the two pistons, a by-pass port in the cylinder and under the control of the scavenging piston, and an exhaust port also under the control of said scavenging piston and arranged to be closed before the by pass port is opened.

In testimony that I claim the foregoing as my own, I have hereto affixed my signature in the presence of two witnesses.

ORIN KELLY.
